UNITED STATES PATENT OFFICE.

JOHN R. FARNUM, OF WALTHAM, MASSACHUSETTS.

SCREEN OR GRID FOR GAS-PURIFIERS.

SPECIFICATION forming part of Letters Patent No. 283,090, dated August 14, 1883.

Application filed April 2, 1883. (No model.)

To all whom it may concern:

Be it known that I, JOHN R. FARNUM, a citizen of the United States, residing at Waltham, in the county of Middlesex and State of 5 Massachusetts, have invented a new and useful Improvement in Screens or Grids for use in Gas-Purifiers, of which the following is a specification, reference being had to the accompanying drawings.

10 My invention relates to screens or grids to be employed in gas-purifiers to support the lime through which the gas is to pass to be purified; and it consists in bars and blocks between the bars, of the construction herein- 15 after specified, and their combination with rods for clamping, as hereinafter set forth.

In the drawings, Figure 1 is a plan view of a screen or grid embodying my invention. Fig. 2 is a side view and Fig. 3 an end view 20 of the same. Fig. 4 is a transverse section of bars and blocks.

The bars A, commonly of wood, I prefer to make of very nearly or quite the shape and proportions shown—namely, each having its 25 upper edge face, a, wider than the lower edge face, b, each side presenting two inclined surfaces, c and d, of like angles of inclination, but one surface, c, wider than the other surface, d.

30 Blocks B are placed between the bars A, each block having each of its two side faces to conform to the surfaces of the side of a bar. Each block, extending at equal distances above and below the line e, at which the two inclined 35 surfaces of a side of a bar meet, will have its upper and lower parts alike, and will be of the same thickness at its upper edge face, f, as at its lower edge face, g.

At the outside of each outside bar half-blocks C are employed, each of which has a side to conform to the side of the bar, but has a plane face, h, to meet a corresponding face of the half-block of an adjacent screen or grid.

45 Through the bars A, blocks B, and half-blocks C rods D extend, which may be riveted at the ends, as shown. There may be as many rows of blocks across the screen as desired, each having a rod, D, extending through 50 the bars, blocks, and half-blocks, and riveted, as stated above. Thus the bars are held at the right distances apart and in true position, and the bars and blocks are firmly clamped together. The rows of blocks near the ends

may be placed so as to extend quite to the 55 ends of the bars, if desired.

Screens or grids constructed as shown and described present no obstruction on their upper surfaces to cause annoyance in shoveling and removing the lime therefrom. While having the bars of sufficient depth for the required strength, the spaces between the bars at their lower edges are wider than the spaces at their upper edges, which tends to facilitate the passage of the gas between the bars. The blocks 65 are readily put in place, since each block has its upper and lower part alike, and hence either part may be made the upper one. The blocks, being made with sides to fit the sides 70 of the bars, formed as specified, act to support the bars about the holes made therein for the rods.

Though I prefer the construction of the bars as specifically pointed out, yet the purposes of my invention could be gained and my 75 invention be involved, as to the whole or a part, if the bars, formed so as to have sides of a rounded or oval shape, or to have any other suitable form, had, in combination therewith, blocks suitably formed to conform thereto and 80 support the bars, as set forth.

I claim as my invention—

1. In a screen or grid, the combination of the bars A, blocks B between the bars, and rods D, extending through the bars and blocks, 85 said bars tapering toward both their upper and lower edges or edge faces, and said blocks conforming to the sides of the bars, substantially as and for the purpose set forth.

2. In a screen or grid, blocks B between the bars thereof, each thinner through the middle than at the upper and lower edge faces, and the upper and lower halves of the block alike, whereby it may be reversed in position, substantially as set forth. 95

3. In a screen or grid, the combination of the bars A, each thicker through the middle than at both the upper and lower edges or edge faces, blocks B between the bars, which are formed at their sides to fit the sides of the bars, half-blocks C, each having one side to conform to the side of a bar, and the rods D, riveted at their ends in said half-blocks, substantially as specified. 100

JOHN R. FARNUM.
